CLAIM

The ornamental design for a can dispenser for refrigerator, as shown and described.

DESCRIPTION

FIG. 1 is a perspective view of a can dispenser for refrigerator, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is a cross-sectional view taken along line 8-8 of FIG. 6; and,

FIG. 9 is an enlarged view of the encircled portion 9 of FIG. 1.

The broken lines illustrating portions of the can dispenser for refrigerator form no part of the claimed design.

The dot-dash broken lines encircling enlargement portions of the design form no part of the claimed design.
